UNITED STATES PATENT OFFICE.

EDWARD T. YOUNG, OF BOSTON, MASSACHUSETTS.

DESIGN FOR A TOY.

SPECIFICATION forming part of Design No. 28,206, dated January 18, 1898.

Application filed October 26, 1897. Serial No. 656,473. Term of patent 7 years.

To all whom it may concern:

Be it known that I, EDWARD T. YOUNG, a citizen of the United States, residing at Boston, in the county of Suffolk and State of Massachusetts, have invented and produced a new and original Design for a Toy, of which the following is a specification, reference being had therein to the accompanying drawings.

Figure 1 of the drawings is an isometric view of the toy, showing my new design. Fig. 2 is a plan view thereof. Fig. 3 is a sectional view taken on the line 3 3 of Fig. 2.

As a unitary article my design consists of a flattened turret or a flattened stepped cone composed of a series of disks 1 1, &c., of progressively-varied diameter, the edge portion of each disk in succession being visible out-

side the periphery of the disk next above and the visible portion of each disk being characterized by one or a plurality of radially-extending slots 2 2, &c. A central perforation 4 is visible in the case of the topmost disk, with a radial slot 2 extending from such perforation to the periphery of the said disk. 20

I claim—

The design for a toy as shown in the accompanying drawings.

In testimony whereof I affix my signature in presence of two witnesses.

EDWARD T. YOUNG.

Witnesses:

CHAS. F. RANDALL,
WILLIAM A. COPELAND.
